(57) **CLAIM**

The ornamental design for a hand truck handle, as shown and described.

DESCRIPTION

FIG. 1 is a perspective view of a hand truck handle stand showing my new design;

FIG. 2 is a top plan view;

FIG. 3 is a side view, the other side view being a mirror image thereof;

FIG. 4 is a front view;

FIG. 5 is a rear view;

FIG. 6 is a bottom view; and,

FIG. 7 is a perspective view showing the hand truck handle of the present invention on a form of a hand truck shown in dotted lines.

The hand truck as shown in dotted lines in FIG. 7 forms no part of the present invention and is for illustrative purposes only.
